UNITED STATES PATENT OFFICE

158,951

DOLL COLLECTOR'S CABINET

Walter S. Gass, Seward, Nebr.

Application June 11, 1948, Serial No. 146,904

Term of patent 14 years

(Cl. D33—19)

To all whom it may concern:

Be it known that I, Walter S. Gass, a citizen of the United States, residing at Seward, in the county of Seward and State of Nebraska, have invented a new, original, and ornamental Design for a Doll Collector's Cabinet, of which the following is a specification, reference being made to the accompanying drawing, forming a part hereof.

In the drawing:

Fig. 1 is a front elevation of a doll collector's cabinet embodying my new design;

Fig. 2 is a rear view; and

Figs. 3 and 4 are vertical and horizontal sectional views taken along the lines 3—3 and 4—4, respectively, in Fig. 1.

The characteristic feature of applicant's design resides in the particular form of the front of the cabinet.

I claim:

The ornamental design for a doll collector's cabinet, substantially as shown and described.

WALTER S. GASS.
